CLASSIFYING DOOR FOR POWER SHOVELS

Walter A. Erickson, Monte Vista, Colo., assignor
of one-half to Alexander T. Erickson, Monte
Vista, Colo.

Application May 29, 1931, Serial No. 541,003
Renewed May 16, 1933

2 Claims. (Cl. 209—419)

This invention relates broadly to power shovels, such as are used in placer mines, and other work of similar nature, as for example excavating and the like.

5 A primary object of this invention is to provide an auxiliary door which may be termed a "classifier door", the purpose of the door being to separate the coarse from the finer material so that the coarse material may be dispensed with 10 subsequent to the discharge of the finer material from the shovel.

Other objects and advantages of the invention will become apparent from a study of the following description, taken in connection with the accompanying drawings wherein:

Figure 1 is a side elevational view of a conventional power shovel, parts being broken away to show the application of my invention thereto.

Figure 2 is a top plan view of the auxiliary 20 bore classifying door.

Figure 3 is a transverse sectional elevational view taken substantially on the line 3—3 of Figure 2.

Figure 4 is a longitudinal sectional elevational 25 view through the auxiliary or classifying door.

With reference more in detail to the drawings, it will be seen that the improved auxiliary or classifying door comprises a frame 5 of the desired shape and dimensions, opposite side members of which frame are connected by parallel transverse ribs 6 and 7.

30 Alternate ribs, that is the ribs 7 have oppositely inclined upper edges 8 merging at their inner ends to a substantially horizontal edge 9. As suggested in Figure 4, the ribs 7 project upwardly beyond the plane of the upper faces of the ribs 6, and these ribs 7 serve to provide against blocking of the openings between the ribs, and also serve as strengthening means for the auxiliary 40 door.

The endmost ribs 7 at their rear ends merge into substantially V-shaped hinge eyes 10 that extend rearwardly beyond the rear side member of the frame 5. The free ends of the hinge eyes 45 10 are pivotally engaged with the pivot bolt 11 usually provided for the swinging closure or door 12 of a conventional power shovel designated generally by the reference character 13. (See Figure 1.)

50 The intermediate rib 7 has its lower portion substantially rectangular in cross section as shown in Figure 4, and through said lower portion extends a longitudinal bore for slidably accommodating the shank 14 that at its forward end is equipped with a beveled latch 15 engageable with a suitable keeper recess provided in a wall of the shovel 13 as will be hereinafter more fully described. The said intermediate rib 7 at its rear end is counterbored for accommodating a coupling socket 16 threadedly engaged with the

rear end of the bolt 14. The socket 16 is provided on one end of a flexible cable 17 which may be operated in any suitable manner for retracting and projecting the latch member 15.

In actual practice, and as shown in Figure 1, the auxiliary or classifying door being hingedly mounted through the medium of the hinge eyes 10 and the hinge bolt 11 serves as an auxiliary closure for the opening 13a of the power shovel.

The auxiliary door when in a closed position fits 65 inwardly of the shovel from the opening 13a and is retained in said closed position by reason of the latch member 15 engaging a keeper recess provided in the forward wall of the shovel 13 as suggested in Figure 1.

Thus it will be seen that the usual door 12 of the shovel may readily swing to an open or closed position with respect to the opening 13 without interference by the auxiliary door constructed in accordance with the present invention.

A power shovel equipped with an auxiliary door as just described, may be operated in the usual manner and upon opening of the usual door 12 of the power shovel, the finer contents of the shovel will discharge therefrom passing between 70 the ribs 6 and 7 of the auxiliary door 5.

The coarser material will be retained in the shovel through the medium of the auxiliary door 5 to be later discharged from the shovel into a suitable hopper or receptacle provided therefor. The discharge of the coarser material from the shovel may be effected by pulling rearwardly or to the right in Figure 1 on the cable 17 thus 75 retracting the latch 15 permitting the auxiliary door to bring about its pivot to an open position through the opening 13a.

80 Thus it will be seen that I have provided an auxiliary door for power shovels, that can be applied to the power shovel without requiring any material alterations in the same, and which 85 will operate for the purpose intended without in any wise interfering with the usual door of the shovel.

Even though I have described and shown 90 herein the preferred embodiment of the invention, it is to be understood that the same is susceptible of changes, modifications and improvements coming within the scope of the appended 95 claims.

Having thus described my invention, what I 100 claim as new is:

1. In a classifying door for power shovels, a frame, a plurality of spaced parallel ribs connected to the sides of the frame, certain of said ribs rising above the plane of the upper faces of the remaining ribs, said certain ribs having upwardly projecting extensions of maximum depth intermediate the ends thereof and being tapered toward the end thereof to constitute a means to hold the larger particles in spaced re- 115

lation to the remaining ribs, thereby allowing smaller particles to pass between the ribs, and attaching means for the frame.

2. In a classifying door for power shovels, a frame, a plurality of spaced parallel ribs connected to the sides of the frame, certain of said ribs rising above the plane of the upper faces of the remaining ribs, said certain ribs having upwardly projecting extensions of maximum depth intermediate the ends thereof and being

tapered toward the end thereof to constitute a means to hold the larger particles in spaced relation to the remaining ribs, thereby allowing smaller particles to pass between the ribs, attaching means for the frame, and a latching mechanism associated with the frame, one of said ribs being provided with a longitudinal passage receiving a portion of said latching mechanism.
